United States Patent Office

Des. 196,877
Patented Nov. 12, 1963

196,877

WALKWAY FRAME

Arthur C. Borgman, Franklin Square, N.Y., assignor to
The Patent Scaffolding Co., Inc., Long Island City,
N.Y., a corporation of New York

Filed June 19, 1959, Ser. No. 56,427

Term of patent 14 years

(Cl. D54—1)

The FIGURE is a front elevational view of a walkway frame showing my new design. The dominant features of my design reside in the portions shown in full lines.

I claim:

The ornamental design for a walkway frame, as shown and described.
